RAILWAY SIGNAL SYSTEM

James A. Parkinson, Topeka, Kans.

Application December 17, 1931, Serial No. 581,546.

14 Claims. (Cl. 246—33)

My invention relates to railway signal systems, and particularly to railway signal systems governing traffic in both directions over a stretch of railway track.

5 I will describe one form of system embodying my invention, and will then point out the novel features thereof in claims.

Figs. 1, 2 and 3, when placed end to end in the order named, constitute a diagrammatic view 10 of one form of system embodying my invention when applied to a stretch of railway extending between two passing sidings designated by the reference characters P1 and P2.

In describing my invention, reference is made 15 to the accompanying drawings wherein like characters of reference designate corresponding parts with a prefix or suffix added to the reference character in many instances to designate the location. In certain instances a circuit controlling contact is located on the drawings at a point remote from the relay controlling the contact in order to simplify the disclosure as much as possible in order that it may be more readily understood. In each instance, such circuit controlling contact is given a reference character 20 having a prefix corresponding to the reference character for the relay controlling the contact, and the position in which the contact is shown corresponds to the normal condition of the relay. 25 For example, the circuit controlling front contact designated by the reference character B1TR²⁰ of Fig. 1 is operated by the track relay B1TR and the contact is shown closed inasmuch as the relay B1TR is normally energized. I shall 30 assume the right-hand end of each view to be east and the left-hand end to be west, and I shall speak of traffic moving from the right to the left as westbound traffic and that moving from the left to the right as eastbound traffic.

40 The traffic rails 1 and 2 are divided into track blocks A—B, B—C, C—D and D—E by the usual insulated rail joints in the customary manner. Each track block is divided into two track sections as will be understood by an inspection of 45 Figs. 1, 2 and 3. In the track block C—D, there is shown a passing siding P3, the track rails of which up to the fouling points are included in the track circuits as is the usual practice. It will be understood that other arrangements of 50 track blocks and sidings differing from that here disclosed may be employed without departing from the scope of my invention. Following standard practice, each track section is provided with a track circuit that includes a source of 55 energy such as a battery 3 connected across the

traffic rails 1 and 2 at one end of the section, and a track relay TR with a prefix corresponding to the location connected to the rails at the opposite end of the section. In connection with the track section at the east end of the passing siding P1, the track relay A2TR is provided with a pick-up circuit that includes a back contact GR⁹¹ of a traffic direction controlling relay GR to be later referred to, and also with a stick circuit that includes its own front contact 92 as will be 10 readily understood by an inspection of Fig. 1. It follows that once the track section at the switch 1S of siding P1 is occupied and track relay A2TR shunted, the relay can be reenergized only when the traffic direction controlling relay GR is de- 15 energized to close the back contact GR⁹¹. The function of this feature in the controlling of the track relay A2TR will appear later in the specification.

The switch controlled relay 1SKR associated 20 with the switch 1S for the passing siding P1 is energized through contacts of a switch circuit controller operated by the movement of the switch 1S in the manner well understood in the art. That is to say, with switch 1S set for main line 25 traffic, the relay 1SKR is energized by current of one polarity and when switch 1S is set for traffic to the siding P1, the relay 1SKR is energized with current of a reverse polarity. In a like manner, the energizing of the switch controlled relay 2SKR 30 is governed by the movement of the switch 2S for the siding P2.

At each location A, B, C, D, and E there is located an eastbound signal designated by the reference character R plus a suffix corresponding to the location, and a west-bound signal L with a suffix corresponding to the location. These signals may be of any standard type and are here shown as three-position searchlight signals. As the mechanisms of the signals form no part of my invention, it is deemed sufficient for this description to point out only the general operation of the signal mechanism. Referring to the signal RB, for example, a spectacle arm designated by the dotted lines 88 is provided at its upper end with three different colored filters 12, 13 and 14 and is operated by the armature 15. The armature 15 is normally biased by means not shown to a position where the filter 13, which is colored red, is brought in alignment with a light 4 and the signal RB displays a stop indication. The field winding 16 is permanently connected to a local source of direct current not shown but indicated on the drawings by the reference character X for the positive terminal and by the reference 55

character Y for the negative terminal. With field winding 17 energized with direct current of one polarity in a manner to be later pointed out, the armature 15 is rotated in a clockwise direction until filter 14, which is colored yellow, is brought in alignment with the light 4 and signal RB displays a caution indication. With field winding 17 energized with current of a reverse polarity, the armature 15 is rotated in a counter-clockwise direction until filter 12, which is colored green, is aligned with light 4 and signal RB displays a clear indication. The armature 15 also actuates two circuit controllers 18 and 19 attached to the armature 15 as indicated by dotted lines. 10 Each of the wayside signals of my system operate in the same manner as that just described for signal RB.

While the light 4 may be illuminated in different ways, a preferred form of lighting circuits is that where the light is normally supplied with current from an alternating current transmission line, and a local standby source of direct current is to be automatically cut into service in the case of a loss of alternating current power. 20 The light 4 of signal RB is normally supplied with current from the secondary 5 of a transformer T, the primary 6 of which is continuously supplied with alternating current from a transmission line not shown. The circuit for the light 4 extends from one terminal of the secondary 5 through the back-contact LBBP⁷ of a relay LBBP associated with the westbound signal LB as will be described later, front contact 8 of a power-off relay PT whose winding is permanently connected to secondary 5, light 4 and front contact 9 to the other terminal of secondary 5. In case of a loss of power from the transmission line, the relay PT is deenergized and its contacts 8 and 9 drop into engagement with back contacts and the light 4 is then supplied from a local standby source of direct current not shown, but whose terminals are designated by the reference characters X and Y. The light circuit now extends from the positive terminal X of the source of direct current, back contact 40 RBGE¹⁰ of a relay RBGE to be referred to later, resistance unit 11, back contact 8 of relay PT, light 4, back contact 9 and to the negative terminal Y of the source of direct current. As will appear later, the back contacts LBBP⁷ and RBGE¹⁰ are closed only upon the approach of a train and thus the signal RB is approach lighted both when the source of current is the alternating current transmission line and when the local standby direct current source is active. The lighting circuits 45 for the westbound signal LB at the same location B are shown in Fig. 1 and are similar to those just described for the signal RB, and thus it is thought not necessary to describe them in detail. It is to be noted, however, that the alternating current transmission line and when the local standby direct current source is active. The lighting circuits 50 circuit is normally held open at the back contact RBEP⁸⁹ of a relay RBEP associated with the eastbound signal RB, and the circuit to the direct current source is normally held open at the back contact LBGE⁹⁰ of a relay LBGE associated with a control circuit for signal LC to the rear of signal LB as will appear as the specification progresses. 55 As the light circuits for the other signals of my system are similar to those described for the signals at the location B and as these light circuits 60 form no part of my invention, the light circuits for the remaining signals are not shown in the drawings for the sake of simplicity. Attention is called to the fact, however, that at any intermediate signal location such as location C, the relay LCBP 65 associated with the westbound signal LC is nor-

mally deenergized at a time when the signal RC is cleared for eastbound traffic in a manner to be later pointed out. Thus the light circuit not shown for the signal RC, which includes a back contact of the relay LCBP in the same manner that the light circuit for the signal LB includes the back contact RBEP⁸⁹, is closed normally and the light continually illuminated. When the local standby source of current is active, however, at such locations, the signal is approach lighted in the same manner as is described above for the signal RB. 10

Associated with each wayside signal are two relays designated by the reference characters HD and NP with prefixes corresponding to the signal. 15 Referring to signal RB, the relay RBHD is supplied with current from the positive terminal X of the local source of current through the controller 18 in either its lower position corresponding to the clear position of signal RB or through its upper position corresponding to the caution position of signal RB, and the winding of the relay to the negative terminal Y of the source of current. The relay RBNP is supplied with current from the positive terminal X through controller 19 in its center position corresponding to the stop position of signal RB and the winding of relay RBNP to the negative terminal Y. It follows that relay RBHD is energized under both the clear and caution positions of signal RB and 20 deenergized under the stop position, while relay RBNP is energized only when signal RB indicates stop. The relay RBHD is made slow-releasing in order that it will remain energized during the interval the signal RB is moved from its caution to clear position or from its clear to caution position. 30

Each wayside signal is provided with a control circuit. Looking at signal LC of Fig. 2, for example, the control circuit for this signal can be traced from the battery 21 at location B through the winding of the low resistance relay LBGE, front contact RBNP²² of relay RBNP associated with the signal RB, back contact 23 of relay LBHD, front contact B1TR²⁰ of track relay B1TR, line wire 24, front contact C2TR²⁵ of track relay C2TR, front contact WFC²⁶ of a directional relay WFC to be described later, field winding 27 of signal LC, line wire 28, back contact 29 of relay LBHD and to the opposite terminal of battery 21. 40 It is to be noted that this control circuit for signal LC is governed by the directional relay WFC, by the track circuits for the track block B-C and by the relay RBNP governed by the position of the opposing signal RB. The polarity of the current supplied to this control circuit for signal LC is governed by the relay LBHD associated with the westbound signal LB in advance. With the signal LB at stop and relay LBHD deenergized, the current is of one polarity and when signal LB is operated to its caution or clear position and relay LBHD energized, the current supplied to the control circuit for signal LC is of a reverse polarity. That is to say, signal LC will display a clear indication when the signal LB in advance displays either caution or clear and will display a caution indication when signal LB is at stop. When the immediate track sections in advance of signal LC are occupied or the opposing signal RB cleared, signal LC is set at stop. Also, the signal LC is manually controlled by means of the directional relay WFC as will shortly appear. 55

The winding of the low resistance relay LBGE being in series with the control circuit for the signal LC, it will be energized whenever that cir- 70 75

cuit is closed. The relay LBGE is also provided, however, with an additional energizing circuit that includes battery 21, winding of relay LBGE, front contact RBBP³⁰ of the relay RBBP, high 5 resistance 31 and back to the battery 21. Except under traffic conditions to be later described, the relay LBGE is retained energized by this last circuit irrespective of the condition of the control circuit for signal LC.

10 Each signal of my system is governed by a control circuit similar to that just described for the signal LC except at certain locations as will now be pointed out. The control circuit for the starting signals RA1 and RA2 at the passing siding P1 receives current from the battery 32 at location B through the winding of the relay RBGE, front contact LBNP³³ of the relay LBNP, pole-changing contact 114 of relay RBHD, a track circuit controlled contact B2TR³⁴ of track relay B2TR, front 15 contact EFB³⁵ of a directional relay EFB to be shortly described, front contact A1TR³⁶ of track relay A1TR, front contact A2TR³⁷ of track relay A2TR, front contact GR³⁷ of the direction controlling relay GR, polar contact GR³⁸, front contact 1SKR³⁹ of relay 1SKR, polar contact 1SKR⁴⁰, field winding 41 of signal RA1 and back to the battery 32 over the line wire 42 through the pole-changing contact 115. With the polar contact 1SKR⁴⁰ shifted to the left-hand position in response to the positioning of the switch 1S for traffic to the siding P1, this control circuit is then connected to the field winding 43 of the signal RA2 as will be readily understood from Fig. 1. The control circuit for the starting signals LE1 and LE2 at the passing siding P2 is modified from that described for the intermediate signals by the including of a contact 44 of a traffic direction controlling lever 45 and by having the circuit first control a polarized relay 46 in place of the field 20 winding of the signals directly. With relay 46 energized by one polarity of current, a circuit is closed from the positive terminal X of a local source of current through the right-hand polar contact 47, front contact 48, a contact 49 governed by a lever of an interlocking machine not shown, in the usual manner, front contact 2SKR⁵⁰, right-hand polar contact 2SKR⁵¹, field winding 52 of signal LE1, front contact 53, right-hand polar contact 54 of relay 46 and to the negative terminal Y. With relay 46 energized by current of a reverse polarity then the current supplied to the field winding 52 will be, in turn, of reverse polarity. When the switch 2S is set for traffic to the siding P2, the polar contact 2SKR⁵¹ is reversed 25 and relay 46 then controls the field winding 55 of signal LE2.

30 Across the signal control circuit, in parallel with the field winding of each intermediate signal, is connected the winding of a relay designated by the reference character BP plus a prefix corresponding to the signal. This relay, however, is connected across the control circuit in advance of the front contact governed by the directional relay. Referring to location C, the relay LCBP 35 associated with the control circuit for signal LC described above is connected to the line wire 24 through the front contact C2TR²⁵ ahead of the front contact WFC²⁶ of the directional relay WFC and is connected to the line wire 28 directly. It follows that relay LCBP may be energized regardless of the position of the directional relay WFC. That is to say, while the signal LC is governed by both traffic conditions in advance and by the directional relay WFC, the relay LCBP is governed by traffic conditions alone. As stated

above, the control circuit for each intermediate signal governs a relay BP in the same manner as just described for relay LCBP.

35 In the figures the apparatus is shown set for eastbound traffic. The manner of establishing the direction of traffic will now be described. Each track block is provided with a traffic control circuit and two directional relays, one for each direction of traffic, designated by the reference character F plus a prefix corresponding to the direction and a suffix corresponding to the location. These traffic control circuits are governed by a traffic direction controlling device located at each of the opposite ends of the stretch of railway. At the passing siding P1, the traffic direction controlling device is the polarized direct current relay GR which is so constructed in a manner well known to the art that its polar contacts will not vibrate open when the relay is de-energized. The means for energizing the relay 40 GR is not shown as it forms no part of my invention. Suffice it to say that this means may be a centralized traffic control system, a remote control system or a local circuit governed by a manually operated lever located at a nearby tower. As a matter of fact, the relay GR may be replaced by a controller actuated by a lever of an interlocking machine should it seem desirable to do so. At the siding location P2, the traffic direction controlling device is shown in the form of a 45 manually operated lever 45 which actuates the controller contacts 44 and 56. Should it seem desirable to do so this lever 45 may be replaced by a relay similar to the relay GR at the opposite end of the stretch. When lever 45 occupies its right-hand position, that is, the position shown in Fig. 3, the contact 56 engages both contact springs 57 and 58. When lever 45 is shifted to its center position or to its left-hand position, the contact 56 becomes disengaged from spring 58 and the circuit controlled thereby is opened.

50 To establish eastbound traffic the operation must begin at the east end of the stretch and proceed as follows: Assuming the track block D—E to be unoccupied, the relay RDBP at the signal location D will be energized, as will be evident by an inspection of Fig. 3 due to the fact that the front contacts D1TR⁵¹, E2TR⁵² and E1TR⁵³ of track relays D1TR, E2TR and E1TR, respectively, are closed. The operator moves the traffic direction controlling lever 45 to its right-hand position and current is supplied from battery 65 through the front contacts LE2NP⁵⁰ and LE1NP⁵⁹ in series, contact spring 57, contact 56, contact spring 58, line wire 66, back contact 67 of westbound directional relay WFD, front contact RDBP⁶⁴ of relay RDBP, winding of eastbound directional relay EFD and line wire 68 back to the battery 65. As directional relay EFD becomes energized, it closes at its front contact 69 a stick circuit around the front contact RDBP⁶⁴. That is to say, the directional relay EFD can be picked up only in the event the track block D—E is unoccupied and the westbound starting signals LE1 and LE2 are at stop, but once it is picked up, a stick circuit is closed that retains the directional relay EFD energized regardless of the traffic conditions of the track block D—E. As directional relay EFD is energized, it also closes front contact EFD⁷⁰ included in the signal control circuit for the signal RD and that signal is then operated to either its caution or clear position depending upon the polarity of the current supplied to its control circuit as determined by the position of

relay REHD associated with the signal RE in advance.

With track block C—D unoccupied so that its track relays C1TR and D2TR are both picked up to close contacts C1TR⁷¹ and D2TR⁷², respectively, and the westbound signal LD is at stop so that the relay LDNP is energized to close front contact LDNP⁷³, the relay RCBP at location C is energized by the control circuit of signal RC. Under these circumstances the energizing of the directional relay EFD closes the traffic control circuit for the block C—D from battery 74 through front contact 75 of relay EFD, line wire 76, back contact 77 of the westbound directional relay WFC, front contact RCBP⁷⁸, winding of relay EFC, line wire 79, front contact 80 and to the opposite terminal of battery 74. As the directional relay EFC picks up, the stick circuit through its own front contact 113 is closed around the front contact RCBP⁷⁸ to retain this directional relay energized regardless of track conditions for the block C—D. Again it is to be noted that before the eastbound directional relay EFC can be energized both the traffic conditions for the track block C—D and the position of the opposing westbound signal LD are checked but after the relay EFC is once energized, neither the position of signal LD nor the traffic conditions of the block C—D affect the relay. As directional relay EFC is picked up, the front contact EFC⁸¹ is closed to complete the signal control circuit to signal RC and that signal is operated in accordance with the position of the relay RDHD for the signal RD in advance.

With the track block B—C unoccupied and the westbound signal LC at stop, current is supplied to the relay RBBP at location B by the control circuit for signal RB in the same manner as described for the relay RCBP at the location C and relay RBBP energized to close the front contact RBBP⁸² included in the circuit for relay EFB. Under these circumstances current flows from the battery 83 at location C through a traffic control circuit that includes the front contacts 84 and 85 of directional relay EFC to energize the eastbound directional relay EFB at location B. This traffic control circuit is similar to that already described for the relay EFC and can be easily traced. As directional relay EFB picks up, a stick circuit is closed through its own front contact 86 to retain this relay energized regardless of traffic conditions for the track block B—C or of the position of the opposing signal LC. The energizing of relay EFB closes the front contact EFB⁸⁷ in the control circuit for signal RB and current is supplied to the field winding 17 of signal RB to operate that signal in accordance with the position of the signal RC in advance.

Assuming the track block A—B to be unoccupied and that the operator has energized the direction controlling relay GR with normal polarity of current to close the contacts GR³⁷ and GR³⁸: The energizing of the directional relay EFB closes the contact EFB³⁵ and thus completes the signal control circuit to signals RA1 and RA2; the circuit being closed to field winding 41 of signal RA1 if the switch 1S is set for main line traffic and closed to field winding 43 of signal RA2 if switch 1S is reversed for traffic to the siding P1.

To sum up thus far, the setting of the direction controlling devices at each end of the stretch of railway in a position corresponding to eastbound traffic causes the traffic control circuits, starting at the east end of the stretch, to be closed successively to energize in turn an east-

bound directional relay at each signal location, if each successive track section of the stretch is unoccupied and each successive opposing west-bound signal is set at stop. When once the directional relays are energized, they are retained energized by stick circuits that make them free from the control of traffic conditions of the track sections and also free from the control exerted by the position of the opposing westbound signals. The energizing of each directional relay completes a signal control circuit for a corresponding eastbound signal to clear that signal in accordance with traffic conditions in advance. It will be noted that while the operator of the relay GR has control over the starting east-bound signals RA1 and RA2, he has no control over the remaining eastbound signals once they have been cleared for an eastbound train. Also it is to be noted that due to the fact the pick-up circuit for the track relay A2TR is controlled through the back contact GR⁹¹ of the relay GR, it is necessary for the operator of relay GR to actuate that relay in order to clear either starting signal RA1 or RA2 for each following eastbound train as well as for the first eastbound train. It is evident that once eastbound traffic has been established, all following eastbound trains will be governed by the automatic signals in accordance with traffic conditions in advance in the same manner as obtained in the usual three-block automatic signal system. As each eastbound train leaves location A, the shunting of the relay A1TR opens front contact A1TR⁹³ and deenergizes the relay LBBP to approach light the signal RB by closing the back contact 35 LBBP⁷ when the normal alternating current source of current is active. In case there is a loss of alternating current power, the signal RB is approach lighted by the standby current source through the back contact RBGE¹⁰ due to the fact that as relay LBBP becomes deenergized, the front contact LBBP⁹⁴ is opened and relay RBGE deenergized inasmuch as the eastbound train has shunted the track relay A2TR to also open front contact A2TR⁹².

To reverse the direction of traffic from that for eastbound trains, in which condition the apparatus of Figs. 1, 2 and 3 is shown, to that for westbound trains, the operator of lever 45 must first reverse the lever to open the circuit to the directional relay EFD. The deenergizing of relay EFD sets signal RD at stop and opens the circuit to relay EFC at the contacts 75 and 80. Relay EFC, in turn, is deenergized to set the signal RC at stop and open the circuit to the directional relay EFB. As relay EFB becomes deenergized, the signal RB is set at stop and the control circuit to the signals RA1 and RA2 opened at contact EFB³⁵ to hold these signals at stop. Assuming that there is no train occupying the stretch between the sidings each BP relay associated with the westbound signal control circuits will be energized due to the fact that the track relays are all picked up and each NP relay associated with the eastbound signals are now energized checking the stop position of the eastbound signals. The operator at the siding P1, that is, at the west end of the stretch, energizes the traffic direction controlling relay GR by current of reverse polarity so that contact 95 is made to engage its left-hand contact and current flows from the battery 96 through contact 97 of relay RNP, left-hand contact 95, line wire 98, back contact 99 of the eastbound directional relay EFB, front contact LBBP¹⁰⁰, winding of directional 55 60 65 70 75

relay WFB and line wire 101 back to the battery 96. As relay WFB picks up, its stick circuit is closed at front contact 102 to retain that relay energized irrespective of traffic conditions of the 5 track block A—B. The signal control circuit for signal LB is now completed at the front contact WFB¹⁶ and that signal operated to either the caution or clear position depending upon the position of the signal LA in advance. The energizing of the directional relay WFB also closes the traffic control circuit for the block B—C from the battery 103 to the directional relay WFC at the front contacts 104 and 105 as will be easily traced. This traffic control circuit being completed through the front contact LCBP¹⁶ of relay LCBP if the opposing eastbound signal RB is at stop so that the contact RBNP²² of relay RBNP is closed and track relays B1TR and C2TR are picked up to close contacts B1TR²⁰ and 10 C2TR²⁵, respectively. As directional relay WFC picks up, it closes its stick circuit at the contact 107 around the front contact LCBP¹⁶ so that this relay is now retained closed irrespective of the traffic conditions of the track block B—C or 15 of the position of the opposing signal RB. The signal control circuit for signal LC is now completed at the front contact WFC²⁶ and that signal operated in accordance with the position of the relay LBHD for signal LB. The energizing of 20 relay WFC also completes the traffic control circuit to the directional relay WFD at the front contacts 77 and 108 so that that relay is now supplied with current from the battery 83 through the front contact LDBP¹⁷ if block C—D is unoccupied and signal RC at stop. As relay WFD is energized, its stick circuit is closed at the contact 109 and it is held energized irrespective of traffic conditions in the track block C—D or of the position of the opposing signal RC. The 25 contact WFD¹⁸ is now closed to complete the control circuit for the signal LD and that signal operated in accordance with the position of the relay LCHD for the signal LC. As relay WFD picks up, the control circuit for the relay 46 is also closed at the contact WFD¹⁹, contact 30 111—44—112 being closed because lever 45 is in its reversed position, and that relay energized in accordance with the position of the relay LDHD for the signal LD. The energizing of the 35 relay 46 permits current to be supplied to either the signal LE1 or LE2 as determined by the position of the switch 2S, it being understood, of course, that the lever controlled contact 49 is closed at this time. With westbound traffic thus 40 established, westbound trains can advance from the location E at the passing siding P2 under the protection of the westbound signals which are now controlled in the usual manner for a three-block automatic signal system; the westbound 45 directional relays remaining energized through the medium of their stick circuits irrespective of the traffic conditions or of the position of the eastbound signals.

It follows from the foregoing description that 46 in establishing a given direction of traffic, the directional relays corresponding to the direction of traffic to be established can be energized only in the event each track section is unoccupied and the opposing signals all in the stop position. Once 50 the direction of traffic is established the directional relays remain energized irrespective of the traffic conditions. It is to be noted also that a directional relay can be energized only in the event the opposing directional relay at the same 55 location is deenergized. For example, the cir-

cuit to relay WFC is controlled by the back contact 84 of the directional relay EFC and the circuit for the relay EFC is likewise controlled by the back contact 77 of relay WFC.

In the case it is desired to have two trains meet at the siding P3 located in the track block C—D, with the westbound train taking the siding, the procedure is as follows: The two operators will first set the relay GR and the lever 45 in the positions to establish westbound traffic in the 10 manner described above and the westbound train advanced from the location E to siding P3 by the clearing of the westbound signals. As this train clears the main track at the siding P3, the operators set the relay GR and the lever 45 in the position to establish eastbound traffic and the eastbound train advanced to the siding P3 by the clearing of the eastbound signals. In order to permit the westbound train to leave the siding P3 and advance west as soon as the eastbound 15 train passes the west end of siding P3, the operator of the lever 45 will place the lever in the center position for a few seconds. This will drop the eastbound directional relays and then if the operator of the relay GR reverses that relay, the 20 westbound directional relays will be energized up to the track block C—D occupied by the eastbound train to clear the westbound signals from signal LC to the location A. The operator of the lever 45 again places this lever in the right-hand 25 position which reenergizes the directional relay EFD to again clear the signal RD for the eastbound train. It follows that these two trains can advance in their corresponding directions from the siding P3 under full signal protection. It 30 would be necessary for the crew of the train on the siding P3 to advise the operators when to execute this operation but this could easily be accomplished by telephone without delay to either train. If the eastbound train is to take siding 35 at P3 the procedure is to establish eastbound traffic to allow the eastbound train to advance to siding P3 and then reverse the direction of traffic and advance the westbound train. If a work train or a pusher engine stops at any intermediate point between the two sidings P1 and P2, the operators can reverse the direction of traffic 40 to permit this work train or pusher engine to return to its starting point under full protection of the signals. Once the direction of traffic is established to advance an eastbound train from the siding P1, switching movements can be made at the west end of the siding P2 without interfering with the eastbound direction of traffic established 45 and thus without delaying the eastbound train but still providing it with the usual automatic signal protection as it approaches the siding P2. In the same manner, switching movements can be made at the east end of the siding P1 after westbound traffic has been established for a westbound train. 50

Such a signal system as here disclosed checks the occupancy of each track section and the stop position of each opposing signal before the direction of traffic can be established. Once the direction of traffic is established the system is free from the danger of a loss of traffic direction due to the possible momentary loss of shunt of a track circuit by a light engine or motor car. Trains may meet at intermediate points and 55 then proceed in opposite directions from the meeting point without delay to either train and under full automatic signal protection. A train may reverse its direction of travel at any intermediate point and the operators establish the 60 65 70 75

direction of traffic corresponding to this reverse movement. Once a train has entered the stretch of railway no opposing train movement can be authorized until the occupying train has cleared 5 the stretch of railway. The direction controlling device may be operated by a centralized traffic control system, a remote control system, or by a local circuit. In fact, any one system may be used to control the traffic controlling device 10 at one end of the stretch and a dissimilar system used to control the traffic controlling device at the other end.

Although I have herein shown and described only one form of apparatus embodying my invention, it is understood that various changes 15 and modifications may be made therein within the scope of the appended claims without departing from the spirit and scope of my invention.

20 Having thus described my invention, what I claim is:

1. A railway signal system including, a stretch 25 of railway track arranged in track sections, signals located at intervals for governing traffic in one direction through the stretch and other signals located at intervals for governing traffic in the other direction through the stretch, a directional relay for each signal adapted when energized to clear said signal, circuit means to control 30 the directional relays arranged to effect the energizing of the relays associated with the signals governing traffic in a given direction only when each track section is unoccupied and each signal governing traffic in the opposite direction is at 35 stop, and means effective when the directional relays for a given direction of traffic are energized to retain said relays energized irrespective of the traffic conditions of the track sections.

2. A railway signal system including, a stretch 40 of railway track arranged in track sections, signals located at intervals for governing traffic in one direction through the stretch and other signals located at intervals for governing traffic in the other direction through the stretch, a directional relay for each signal adapted when energized to clear said signal, circuit means to control 45 the directional relays arranged to effect the energizing of the relays associated with the signals governing traffic in a given direction only when each track section is unoccupied and each signal governing traffic in the opposite direction is at stop, and means effective when the directional relays for a given direction of traffic are energized to retain said relays energized irrespective of the traffic conditions of the track sections or of the position of the opposing signals.

3. A railway signal system including, a stretch 50 of railway track arranged in track sections, signals located at intervals for governing traffic in one direction through the stretch and other signals located at intervals for governing traffic in the other direction through the stretch, a directional relay for each signal adapted when energized to clear said signal, circuit means to control 55 the directional relays arranged to effect the energizing of the relays associated with the signals governing traffic in a given direction only when each track section is unoccupied, and a stick circuit for each relay effective when the directional relays for a given direction of traffic are once energized to retain its relay energized irrespective of the traffic conditions of the track sections.

4. A railway signal system including, a stretch 75 of railway track arranged in track sections, sig-

nals located at intervals for governing traffic in one direction through the stretch and other signals located at intervals for governing traffic in the other direction through the stretch, a directional relay for each signal adapted when energized to clear said signal, a manually controlled circuit means to control the directional relays capable of energizing the relays associated with the signals governing traffic in one direction or energizing the relays associated with the signals governing traffic in the other direction only when each track section is unoccupied, and thereby clear the signals for one direction or the other, and a stick circuit for each relay effective when the directional relays for a given direction of traffic are once energized to retain its relay energized irrespective of the traffic conditions of the track sections.

5. A railway signal system including, a stretch 20 of railway, signals located at opposite ends of the stretch to govern traffic in opposite directions through the stretch, a control circuit for each signal responsive to traffic conditions of the stretch, a traffic direction controlling circuit, a directional relay for each signal adapted when energized to clear the signal controlled jointly by the traffic direction controlling circuit and the control circuit for the same signal, means rendered effective to control a directional relay by the traffic direction controlling circuit only, 30 once the relay is energized, and a manually operated device to control the traffic direction controlling circuit.

6. A railway signal system including, a stretch 35 of railway, signals located at opposite ends of the stretch to govern traffic in opposite directions through the stretch, a control circuit for each signal responsive to traffic conditions of the stretch, a directional relay for each signal, a traffic direction controlling circuit, means controlled 40 jointly by the control circuit of a signal and the traffic direction controlling circuit to energize the directional relay associated with that signal, means controlled jointly by the control circuit and the directional relay to clear the signal, 45 means to annul the control of the control circuit over the directional relay once said relay is set to clear its signal, and manually operated devices to control said traffic direction controlling circuit.

7. A railway signal system including, a stretch 50 of railway arranged in a plurality of track blocks, a signal located at each end of a track block to govern traffic in opposite directions through the block, a traffic direction controlling circuit for each track block for controlling the signals, traffic controlled means for each track block responsive to traffic conditions of the block, a manually operated device adapted to act in conjunction with the traffic controlled means for causing the traffic direction controlling circuits to establish a given 55 direction of traffic through the stretch, and means associated with each traffic direction controlling circuit to annul the control of the traffic controlled means over said traffic direction controlling circuit once the direction of traffic has been established.

8. A railway signal system including a stretch 70 of railway arranged in a plurality of track blocks, a signal located at each end of a track block to govern traffic in opposite directions through the block, a traffic direction controlling circuit for each track block for controlling the signals, traffic controlled means for each track block responsive to traffic conditions of the block, a circuit 75

- controlling device for each signal governed by the position of the signal, a manually operated device adapted to act in conjunction with the traffic controlled means and the circuit controlling devices 5 for causing the traffic direction controlling circuits to establish a given direction of traffic through said stretch, and means associated with each traffic direction controlling circuit to annul the control of the traffic controlled means and the 10 circuit controlling devices over said traffic direction controlling circuit once the direction of traffic has been established.
9. A railway signal system including, a stretch of railway over which traffic normally moves in either direction, a first set of signals located at 15 intervals to govern trains through the stretch in one direction, a second set of signals located at intervals to govern trains through the stretch in the opposite direction and arranged that there is 20 a signal of the second set located opposite each signal of the first set, traffic direction controlling circuit means to selectively control said first and second set of signals arranged to clear the signals of a set by starting at the remote end of the 25 stretch and clearing the signals successively, a signal device controlling said traffic direction controlling circuit means to check the stop indication of the opposing signal of each of the successive signals of the set selected before the signal 30 can be cleared, and means controlled by said traffic direction controlling circuit means to annul the control of said traffic direction controlling circuit means by said signal device once a set of signals has been cleared.
- 35 10. A railway signal system including, a stretch of railway, a first set of signals located at intervals to govern traffic in one direction through the stretch, a second set of signals located at intervals to govern traffic in the opposite direction through 40 the stretch, a control circuit for each signal responsive to traffic conditions in advance of the signal, and a manually controlled circuit means to establish the direction of traffic adapted to act in conjunction with the control circuits to selectively 45 clear one or the other of said set of signals when said stretch is unoccupied to permit a train to enter said stretch, said manually controlled circuit means capable of reversing the direction of traffic to the rear of a train occupying any 50 intermediate point of the stretch and act in conjunction with the control circuits to clear the opposing signals in the rear of said train and thereby permit a train to travel in the reverse direction from said intermediate point.
- 55 11. A railway signal system including, a stretch of railway, a first set of signals located at intervals to govern traffic in one direction through the stretch, a second set of signals located at intervals to govern traffic in the opposite direction 60 through the stretch, a track circuit for each signal responsive to traffic conditions in advance of the signal, and a manually controlled means to establish the direction of traffic adapted to act in conjunction with the track circuits to selectively clear one or the other of said set of signals when said stretch is unoccupied to permit a train to traverse said stretch, said manually controlled means capable of reversing the direction 65 of traffic to the rear of a train occupying any intermediate point of the stretch and cooperate with said track circuits to clear the opposing signal to the rear of said train and thereby 70
- permit traffic in the reverse direction from said intermediate point.
12. In combination, a stretch of railway track, a signal at each end of the stretch to govern traffic in opposite directions through the stretch, a traffic locking circuit for the stretch divided into a plurality of different sections, a source of current and a relay at each end of the stretch, manually controlled means at each end of the stretch to connect either the current source or the relay at such end to the traffic locking circuit, repeating means at each junction of adjacent sections of the traffic locking circuit including two directional relays controlled by said circuit and arranged to supply current to the left-hand section in response to control by current from the right-hand section or to supply current to the right-hand section in response to control by current from the left-hand section for energizing the relay at the end of the stretch opposite that at which the current source is connected to the traffic locking circuit, and means controlled by the relay at each end of the stretch for governing the signal located at its end.
13. A railway signal system including, a stretch of railway, a first set of signals located at intervals to govern traffic in one direction through the stretch, a second set of signals located at intervals to govern traffic in the opposite direction through the stretch, a signal control circuit for each signal responsive to traffic conditions in advance of the signal, a traffic control circuit for each signal, manually controlled means for governing the traffic control circuits to select the direction of traffic, and means controlled jointly by the traffic control circuits and the signal control circuits to selectively clear the set of signals corresponding to the direction selected by the manually controlled means, and said traffic control circuits arranged in such a manner as to permit the manually controlled means to reverse the direction of traffic to the rear of a train occupying any intermediate point of the stretch whereby the signals will be cleared for a train to move in the reverse direction from said intermediate point.
14. A railway signal system including, a stretch of railway, a first set of signals located at intervals to govern traffic in one direction through the stretch, a second set of signals located at intervals to govern traffic in the opposite direction through the stretch, a control circuit for each signal responsive to traffic conditions in advance of the signal, a traffic control circuit for the stretch and divided into a plurality of different sections, two directional relays located at each junction of adjacent sections of the traffic control circuit, manually controlled means to govern the traffic control circuit to selectively energize the directional relays at each junction to establish the direction of traffic, means controlled jointly by the directional relays and said control circuits to selectively clear one set or the other of said signals, and said traffic control circuit arranged in such a manner as to permit the manually controlled means to reverse the selection of the directional relays at all junctions to the rear of a train occupying any intermediate point of the stretch whereby the opposing signals may be cleared for a train to move in the reverse direction from said intermediate point.

JAMES A. PARKINSON.
